UNITED STATES PATENT OFFICE.

WILLIAM D. JONES, OF NEW YORK, N. Y., ASSIGNOR OF ONE-THIRD TO WILLIAM A. REES AND ONE-THIRD TO RICHARD L. REES, BOTH OF NEW YORK, N. Y.

ELECTRIC WASHING-MACHINE.

1,020,829.

Specification of Letters Patent. Patented Mar. 19, 1912.

Application filed December 11, 1911. Serial No. 665,020.

To all whom it may concern:

Be it known that I, WILLIAM D. JONES, a citizen of the United States, and a resident of the city of New York, borough of Manhattan, in the county and State of New York, have invented a new and Improved Electric Washing-Machine, of which the following is a full, clear, and exact description.

The invention relates to washing machines in which an electric circuit is passed through the washing liquid.

The object of the invention is to provide a new and improved electric washing machine arranged to facilitate the washing of the clothes and to insure the setting or fixing of the colors of the cloth materials by passing the electric current in different planes through the washing liquid, and by simultaneously starting the rotation of the revolvable cylinder containing the clothes and passing the electric current through the washing liquid.

For the purpose mentioned use is made of oppositely-disposed sets of electrodes arranged within a tank or a vat containing a washing liquid, and a revolvable perforated cylinder for the clothes to be washed and means for electrically-connecting the electrodes in the sets in any predetermined manner to cause the electric current to pass through the washing liquid in different planes.

A practical embodiment of the invention is represented in the accompanying drawings forming a part of this specification, in which similar characters of reference indicate corresponding parts in all the views.

Figure 1 is a longitudinal central section of the electric washing machine; Fig. 2 is an enlarged face view of one of the sectional electrodes; Fig. 3 is a sectional plan view of the same on the line 3-3 of Fig. 2; Fig. 4 is a transverse section of the same on the line 4-4 of Fig. 2; and Fig. 5 is a diagrammatic view of the electric connection between the electrodes and the commutator.

A tank or vat A of suitable size is adapted to contain water or other washing liquid B, and the said tank is provided with a cover C, and within the tank is arranged a receptacle for containing the clothes, preferably in the form of a revolvable perforated cylinder D having its shaft E journaled in suitable bearings arranged on the ends of the tank A. The shaft E is driven from a revers-

ing device F by suitable gearing G and the said reversing device F is provided with a fast pulley F' flanked by loose pulleys F², F³ and a belt H connects the said pulleys with fast and loose pulleys H', H² of a driven countershaft, and the said belt H is engaged by a belt-shifting lever I for stopping and starting the washing machine on shifting the belt from the fast pulley to the loose pulley.

Within the tank A and preferably at the ends thereof are arranged two sets of oppositely-disposed electrodes J, J', J², J³ and J⁴, J⁵, J⁶, J⁷, of which the set of electrodes J, J', J² and J³ are mounted on an insulating plate K, and the electrodes J⁴, J⁵, J⁶, J⁷ are mounted on an insulating plate K' and the said insulating plates K and K' are fastened to the inner surfaces of the ends of the tank A. Each of the electrodes and the plates K, K' are preferably of the construction shown and described in the application for Letters Patent of the United States, Serial No. 665,029, filed under even date herewith, so that further description of the sets of electrodes and insulating plates is not deemed necessary.

The electrodes J, J', J², J³, J⁴, J⁵, J⁶, and J⁷ are provided with contact pins L, L', L², L³, L⁴, L⁵, L⁶ and L⁷ held in insulated bushings K², K³ arranged in the ends of the tank A, and the outer ends of the said contact pins L, L', L², L³, L⁴, L⁵, L⁶ and L⁷ are connected with a commutator which rotates in unison with the revolvable receptacle or cylinder D.

The commutator is arranged as follows: The pins L, L', L², L³, L⁴, L⁵, L⁶, L⁷ are connected by wires O, O', O², O³, O⁴, O⁵, O⁶, O⁷ with brushes P, P', P², P³, P⁴, P⁵, P⁶ and P⁷ in peripheral engagement with commutator collecting rings Q, Q', Q², Q³, Q⁴, Q⁵, Q⁶ and Q⁷ insulated on a shaft R provided with a pinion R' in mesh with the gearing G so that when the cylinder D is rotated a rotary motion is transmitted to the shaft R and the rings Q, Q', Q², Q³, Q⁴, Q⁵, Q⁶ and Q⁷ carried thereby. The rings Q, Q', Q², Q³, Q⁴, Q⁵, Q⁶ and Q⁷ are electrically connected by wires S, S', S², S³, S⁴, S⁵, S⁶ and S⁷ with the sections T, T', T², T³, T⁴, T⁵, T⁶ and T⁷ of the rim of the commutator wheel T⁸ secured on the shaft R and rotating with the same, the sections T, T', T², T³, T⁴, T⁵, T⁶ and T⁷ being insulated one from the

other. Brushes U and U' arranged diametrically opposite each other are in contact with the sections T, T', T², T³, T⁴, T⁵, T⁶ and T', and the brushes are connected with wires U², U³, of which the wire U² contains a source of electrical energy V and the wire U³ is connected with the fixed contact member W of a switch having a movable member W' connected by an insulated link W² with the shifting lever I, so that when the machine is started then the movable member W' of the switch is thrown in contact with the contact W to close the electrical circuit simultaneously with the rotating of the cylinder D. In a like manner when the lever I is moved in the reverse direction to stop the machine then the contact member W' is moved out of contact with the fixed contact W to break the electric circuit for the commutator.

When the machine is running and the shaft R is rotating then the electrodes J and J⁴ are first rendered active so that an electric current passes from the electrode J to the electrode J⁴ by way of the liquid B contained in the tank A and in a plane passing through the electrode J, J⁴, and then the current is cut off from the said electrodes J, J⁴ and the electrodes J', J⁵ are connected with each other so that the current now passes through the washing liquid in a plane passing through the said electrodes J', J⁵. The electrodes J', J⁶ are next cut out and the electrodes J², J⁶ are connected with each other, that is, are rendered active so that the electric current passes through the washing liquid in a plane passing through the electrodes J², J⁶, and the electrodes J², J⁶ are next cut out and rendered inactive while the next following electrodes J³, J⁷ are rendered active so that the electric current passes through the washing liquid in a plane passing through the electrodes J³, J⁷. The electrodes J³, J⁷ are next rendered dormant and the electrodes J, J⁴ are again rendered active and the above-described operation is repeated, that is, the electric currents are successively passed through the washing liquid in different planes whereby the washing of the clothes is facilitated and a setting or fixing of the colors contained in the clothes to be washed takes place.

It is understood that the electrical impulses given to the washing liquid in different planes and in any desired order aids the setting of the colors in the clothes and helps the washing thereof, and as the cylinder D is not rotated until the currents are turned on, it is evident that the colors are not liable to run as would be the case if the cylinder D were started and ran for awhile, prior to turning on the electric current.

It is understood that the electrodes in the

two sets are electrically connected with each other in rotation by the commutator, but the order in which the pairs of electrodes are connected with each other may be varied. As shown, the electrodes directly opposite each other are rendered active at a time, but electrodes arranged diagonally opposite each other may be rendered active, that is, connected with each other by changing, for instance, the wiring O, O', O², O³, relative to the electrodes J, J', J² and J³; or the wiring O⁴, O⁵, O⁶ and O' relative to the electrodes J⁴, J⁵, J⁶ and J⁷. Thus the electrodes J and J' may, for instance, be connected with each other, and likewise the electrode J' may be connected with the electrode J⁶, the electrode J² with the electrode J⁵ and the electrode J³ with the electrode J⁴, so that the electric currents pass in rotation and in diagonal planes through the washing liquid.

Having thus described my invention, I claim as new and desire to secure by Letters Patent:

1. An electric washing machine, comprising a tank adapted to contain a liquid, a perforated revoluble receptacle in the said tank, oppositely-disposed sets of electrodes within the tank, and means for connecting the electrodes in the sets with each other in rotation to cause electrical currents to pass through the liquid in different planes.

2. An electric washing machine, comprising a tank adapted to contain a liquid, a perforated revoluble receptacle in the said tank, oppositely-disposed sets of electrodes within the tank, and a commutator rotating in unison with the said receptacle and electrically connected with the said electrodes.

3. An electric washing machine, comprising a tank adapted to contain a liquid, a perforated revoluble receptacle in the said tank, oppositely-disposed sets of electrodes within the tank, a commutator rotating in unison with the said receptacle and electrically connected with the said electrodes, a switch for the commutator, and manually-controlled means for controlling the said switch and for stopping and starting the said revoluble receptacle.

4. In combination with a tank adapted to contain a liquid, opposite sets of electrodes in the said tank, and a commutator connecting the electrodes in the sets with each other in rotation to cause electric currents to pass through the liquid in different planes.

In testimony whereof I have signed my name to this specification in the presence of two subscribing witnesses.

WILLIAM D. JONES.
